UNITED STATES PATENT OFFICE

145,500

DESIGN FOR A STEAK PLATTER OR SIMILAR ARTICLE

Benjamin H. Adler, Chicago, Ill.

Application November 3, 1945, Serial No. 123,433

Term of patent 14 years

(Cl. D44—15)

To all whom it may concern:

Be it known that I, Benjamin H. Adler, a citizen of the United States, residing at Chicago, in the county of Cook and State of Illinois, have invented a new, original, and ornamental Design for a Steak Platter or Similar Article, of which the following is a specification, reference being had to the accompanying drawing, forming part thereof, in which

Fig. 1 is a plan view of the inner face of a steak platter showing my new design; and

Fig. 2 is a transverse sectional view, taken on the line 2—2 of Fig. 1.

The dominant features of my design reside in the portions shown in full lines.

I claim:

The ornamental design for a steak platter or similar article, as shown and described.

BENJAMIN H. ADLER.
